UNITED STATES PATENT OFFICE.

WILLIAM CROMWELL GURNEY, OF TORONTO, ONTARIO, CANADA, ASSIGNOR TO
GURNEY HEATER MANUFACTURING COMPANY, OF BOSTON, MASSACHU-
SETTS, A CORPORATION OF MASSACHUSETTS.

SMOKE-CONSUMING BOILER.

1,163,655.

Specification of Letters Patent. Patented Dec. 14, 1915.

Application filed June 15, 1914. Serial No. 845,326.

To all whom it may concern:

Be it known that I, WILLIAM CROMWELL GURNEY, a British subject, and resident of the city of Toronto, in the county of York 5 and Province of Ontario, Dominion of Canada, have invented certain new and useful Improvements in Smoke-Consuming Boilers; and I hereby declare that the following is a full, clear, and exact description of the 10 same.

My invention relates to the peculiar construction and arrangement of the fire and combustion chambers of a hot water or steam boiler, one of the objects of my invention being to provide the fire chamber with a hollow water grate, connected with the water or steam spaces of the assembled boiler sections, which will permit of the gas from the decomposing fuel passing to the 15 underside of the grate where a consuming fire is maintained in a secondary fire chamber, a suitable opening being provided below the grate for the passage of the consumed or partly consumed gas from the fire 20 chamber to the combustion chamber; another object of my invention being to construct the hollow water grate of separated sections whereby they can contract and expand independently of each other as a result 25 of the variations of temperature in the fire chamber; and a further object of my invention is to provide the secondary fire chamber with grate bars to receive the droppings from the fire above it, whereby such 30 droppings will not only be completely consumed, but can be utilized for the combustion of the gas passing downwardly from the main fire, as hereinafter set forth and particularly pointed out in the claim.

40 In the drawings Figure 1, is a sectional perspective view of a hot water or steam boiler showing the construction and arrangement of the essential parts of the invention. Fig. 2 is a broken sectional view 45 showing the hollow fire grate in circulation with the boiler sections.

The boiler may be composed of any desired number of boiler sections *a* assembled to form water or steam spaces inclosing the 50 fire chamber *b*. In the fire chamber *b* is a hollow water grate connected with the water or steam spaces of the boiler sections so that a circulation of water may be maintained through the grate. In the grate are

flue openings *d* through which the gas 55 passes from the burning fuel on the grate and through which the droppings from the fire may pass into the secondary fire chamber *e*, where not only their complete combustion occurs but where they are utilized 60 for the combustion of the gas passing downward through the grate, and at the bottom of the secondary fire chamber *e* are grate bars *f* of the usual construction.

The hollow water grate may be made in 65 two or more sections *c* and *c'*, the grate sections *c* being connected to and in circulation with the boiler sections *a* at one side of the fire chamber *b* and in line with the grate sections *c'* connected to and in circulation 70 with the boiler sections at the other side of the fire chamber. When the water grate consists of two grate sections, each section extends slightly less than half way across the fire chamber *b* so that an unoccupied 75 space *c''* will be formed between the grate sections; the purpose of this construction being to permit of the unimpeded expansion and contraction of the grate sections independently of each other as a result of the 80 variation of temperature in the fire chamber.

As shown in the drawings, a set of water tubes *g* are located in the top of the fire chamber *b* so that the heated gas within the fire chamber can heat the water in such 85 tubes, and a set of water tubes *h* are located below the water grate so that the flames and heated gas passing through the openings *d* can heat the water in such tubes.

In the rear of the fire chambers *b* and *e* 90 is a combustion chamber *i* in which are located water tubes *j*, the water tubes *j*, *h* and *g* being in circulation with the boiler sections *a*. Between the fire and combustion chambers is a bridge wall *k*, and 95 formed through the bridge wall *k* below the water grate *c* is an opening *l* through which the burning gas passes from the fire chamber *e* to the combustion chamber.

In the fire chamber *b* above the water 100 grate are draft openings *m* and below the grate bars *f* are draft openings *o*. At the back of the combustion chamber *i* is a smoke outlet *p*.

In the operation of the furnace, soft coal 105 slack is introduced into the fire chamber *b* through the fire doors *q*, and when so introduced the fire within the fire chamber de-

composes or converts it into gas which is mixed with sufficient oxygen admitted through the draft openings *m* to form carbon-monoxide. This gas then passes down-
wardly through the openings *d* into the secondary fire chamber *e* where it is consumed or partly consumed before it passes there-
from through the opening *l* into the combus-
tion chamber *i*. As the gas passes down-
wardly the solid carbon which may have
been given off is deposited upon the fire in
the secondary fire chamber *e* and is con-
sumed by the burning coals on the grate bars
f, so that when the gas passes into the com-
bustion chamber *i* it will be practically free
from solid carbon, and what little carbon is
carried into the combustion chamber by the
gas will be completely consumed by the
flames therein before the gas escapes to the
smoke outlet *p*.

The operation of the boiler may be briefly summarized by stating; that the fire is built on the grate which is hollow to form a water section in circulation with the boiler sections *a*; that fresh air is taken in above this fire and the flames and gas plunge downwardly through the flue openings in this grate; that some of the burning fuel drops through these flue openings on to the grate bars *f* at the bottom of the secondary fire chamber and forms an incandescent fire thereon; that the gas bursts into flame as it passes over the secondary fire and is mostly consumed before passing into the combustion chamber; that the products of combustion from both fires then enter the combustion chamber in the rear of the fire chambers where their combustion is completed as they pass

in the zig-zag course between the series of water tubes to a smoke outlet; that the gas in its passage through the tubes is cooled before it reaches the flue; that the smoke, when it reaches the smoke outlet, is practically as colorless as that from an anthracite fire and that by constructing the water grate in separated sections provision is made for the expansion of these grate sections toward the center of the boiler casing; and the possibility of the expansion of the grate sections forcing the boiler sides outward is thus avoided.

Having thus fully described the nature of my invention, what I claim as new and desire to secure by Letters Patent, is:

A boiler composed of a set of assembled boiler sections forming water or steam spaces inclosing a fire chamber, a hollow grate within the fire chamber consisting of two sets of grate sections, the grate sections of one set being connected to and in circulation with the boiler sections at one side of the fire chamber and the grate sections of the other set being connected to and in circulation with the boiler sections at the other side of the fire chamber and in line with those of the first set, with an unoccupied space between the grate sections of each set whereby each set of grate sections can expand and contract independently of the other.

Toronto, May 13th, 1914.

WILLIAM CROMWELL GURNEY.
